United States Patent Office

Des. 191,546
Patented Oct. 10, 1961

191,546

COMBINED REFUSE CAN AND PAIL

Abel E. Garner, 480 Park Ave., New York, N.Y.

Filed July 13, 1960, Ser. No. 61,348

Term of patent 3½ years

(Cl. D58—17)

Fig. 1.

Fig. 2.

Fig. 3.

Fig. 4.Fig. 5.Fig. 6.

FIG. 1 is a front perspective view of a combined refuse can and pail showing my new design;

FIG. 2 is a rear perspective view thereof;

FIG. 3 is a front perspective view thereof, shown in open position;

FIG. 4 is an enlarged perspective view thereof, showing the pail removed from the can.

FIG. 5 is a horizontal sectional view taken on the line 5—5 of FIG. 3; and

FIG. 6 is a bottom plan view thereof.

I claim:

The ornamental design for a combined refuse can and pail, substantially as shown.
